UNITED STATES PATENT OFFICE.

EDWIN S. VOTEY, OF SUMMIT, NEW JERSEY, ASSIGNOR TO AEGLIAN COMPANY, OF NEW YORK, N. Y., A CORPORATION OF CONNECTICUT.

DETACHABLE MUSIC-ROLL SUPPORT.

No. 849,091.

Specification of Letters Patent.

Patented April 2, 1907.

Application filed May 1, 1905. Serial No. 258,211.

To all whom it may concern:

Be it known that I, EDWIN S. VOTEY, a citizen of the United States, and a resident of Summit, New Jersey, have invented certain new and useful Improvements in Detachable Music-Roll Supports, of which the following is a specification.

My invention relates to means for supporting a music-roll in a mechanical musical instrument or mechanical player for musical instruments.

It provides a coupling device whereby a roll having hollow ends may be suitably supported between the ends of the roll-supporting shafts on the instrument.

It is particularly adapted for use with a new form of music-roll invented by me and for which I have filed a copending application of even date herewith, which application has received Serial No. 258,210, also No. 282,660, filed October 13, 1905. In this application the roll is hollow, or at least has circular recesses at its ends, the bead or flange which forms the margin of said recess at one end of the roll being preferably notched or recessed for engagement with a co-operating driving-clutch member, by which it may be engaged with the driving-shaft for rewinding the roll.

In the drawings, Figure 1 represents so much of a mechanical musical instrument as is necessary to show my invention, together with the music-roll and my novel supports. Figs. 2 and 3 are inner end views of the two supports shown in Fig. 1. Fig. 4 is a longitudinal section, on a larger scale, of parts shown at the right end of the roll, Fig. 1.

1 designates the driving-shaft of a mechanical musical instrument, shown as provided with a non-circular axial recess 11 at its free end adapted to receive the non-circular pin of the ordinary music-roll. 12 designates the sprocket-chain, by which the shaft 1 is driven when the music-sheet is rewound on the roll. 2 designates an idler-shaft also provided with an axial recess 21 for receiving the pin of the ordinary music-roll. The idler-shaft 2 is free as to longitudinal movement through the partition or board 3 and is provided with a spring 211 to insure its return to its operative position and to hold the roll-supports pressed toward each other and with a pin 22 moving in a slot 31 for purposes for-

sign to the present invention and incidentally to assist in maintaining it in its proper relative position.

4 designates a music-roll, having end flanges 41 and tubular sleeves 42, having outturned flanges or beads 43 engaging over the inner edges of the flanges 41, one of the beads 43, that shown at the right of Fig. 1, being provided with a notch or recess 44, the function of which will hereafter appear.

5 designates one of my roll-supports, provided at one end with a circular portion 51, adapted to engage in the end of the sleeve 42 and center and support the roll 4. Adjacent the portion 51 is a laterally-extending flange or rim 52, having a recess 53 adapted to engage over the bead 43 on the sleeve 42 and having a tooth 54 for engagement in the recess 44 in the bead. At the other end of the socket or support 5 is a recess 55, adapted to fit smoothly over the end of the shaft 1. A set-screw 56 passes through the wall of the recess 55 and serves to lock the support 5 onto the end of the shaft 1.

The support 6 (shown at the left end of the roll in the drawings, Fig. 1) has a centering portion 61, adapted to enter the end of the sleeve 42, a flange or rim 62, adapted to bear against the bead 43 of the sleeve, a recess 63, adapted to fit over the end of the shaft 2, and a set-screw 64, adapted to engage with the shaft and positively lock the socket or support 6 in position. As shown, the flanged portion 62 of the support 6 is rotatable on the body portion, the two being engaged by the pin 65.

The operation and function of the device will be clearly seen from an inspection of the drawings. It is obvious that the relatively short roll 4 would not extend the entire distance between the ends of the shafts 1 and 2. Neither is it provided with centering-pins to enter the recesses 11 and 21 in the ends of these shafts. It is, however, suitably centered and supported—e. g., by the engagement in its recessed ends of the portions 51 and 61 of the supports 5 and 6, respectively—and is positively driven by the engagement of the tooth 54 on the support 5 with the recess 44 in the bead 43 of the sleeve 42 at one end of the roll.

It is obvious that certain mechanical

changes may be made in my device without departing from the spirit of the invention.

In my copending application, Serial No. 258,210, above referred to, I have claimed 5 the combination of a music-roll substantially such as herein shown, with the clutch member of a mechanical musical instrument similar to that on one of the coupling members shown herein. I do not, therefore, in this 10 application make any claim to such combination.

What I claim is—

1. A music-roll coupling having at one end a projecting centering portion for entering 15 the hollow end of the music-roll, an outwardly-extending portion formed with an annular recess, and a coupling member in said recess, and at its other end a recess for detachably engaging a shaft.
2. A music-roll coupling for a mechanical musical instrument having at one end a projecting centering portion for entering the hollow end of a music-roll and an outwardly-extending portion for bearing against the end 25 of such roll, and at its other end a recess for engaging the end of a shaft and means independent of any stationary portion of said instrument for detachably securing the coupling on such shaft.
3. A music-roll coupling for a mechanical musical instrument having at one end a projecting centering portion for entering the hollow end of a music-roll, an outwardly-extending portion for bearing against the end 35 of such roll and a coupling member for engaging with a coupling member on such roll, and at its other end a recess for engaging the end of a shaft and means for detachably engaging such shaft independent of any stationary portion of said instrument.
4. A music-roll coupling having at one end a projecting centering portion for entering the hollow end of a music-roll, an outwardly-extending portion formed with an annular 45 recess for engaging a bead at the end of such roll and a tooth in said recess for engaging a corresponding notch in such bead, and at its other end a recess for detachably engaging a shaft.
5. A music-roll coupling comprising a shaft-engaging portion recessed to engage the end of the shaft, means for securing said portion on the shaft, and a centering portion for entering the hollow end of a music-roll, 55 said centering portion being provided with an outwardly-extending portion for bearing against the end of the roll and being rotatably mounted on said shaft-engaging portion.
6. A pair of music-roll couplings, each 60 having means for detachably engaging the end of a shaft, an inwardly-projecting centering portion for entering the hollow end of a music-roll, and a flange for bearing against the end of the roll, one of said couplings hav-
- ing means for driving engagement with the 65 roll, and the other coupling having a rotary bearing between its shaft-engaging means and its centering portion.
7. A music-roll coupling having at one end means for supporting a music-roll in alignment with a roll-supporting shaft of a mechanical musical instrument, and formed with an annularly-recessed portion and a coupling member in such recess, and at its other end a recess for detachably engaging a 75 shaft.
8. A music-roll coupling having at one end means for supporting a music-roll in alignment with the roll-supporting shaft of a mechanical musical instrument, and formed with an annularly-recessed portion and at its other end a recess for engaging the end of a shaft, and means for detachably securing the coupling on such shaft.
9. A music-roll coupling for a mechanical 85 musical instrument provided with a roll-supporting shaft, said coupling having at one end a projecting centering portion for entering the hollow end of a music-roll and an outwardly-extending portion for bearing against the end of such roll and at its other end a recess for engaging the end of the shaft, and means for detachably securing the coupling on said shaft, said shaft having an axial recess for receiving the pin of a solid-end music- 95 roll.
10. A music-roll coupling for a mechanical musical instrument provided with a roll-supporting shaft, said coupling having at one end a projecting centering portion for entering the hollow end of a music-roll, an outwardly-extending portion for bearing against the end of such roll and a coupling member for engaging with the coupling member on such roll and at its other end a recess for 105 detachably engaging the end of said shaft, said shaft having a non-circular axial recess for receiving the pin of a solid-end music-roll.
11. A mechanical musical instrument having roll-carrying journals forming parts thereof, in combination with a tubular music-roll, and means normally and detachably secured to said journals for centering and driving said roll.
12. A mechanical musical instrument having roll-carrying journals, one of said journals being the usual driving-journal and the other the usual spring-pressed co-operating journal, in combination with a flanged plug 115 detachably secured to said driving-journal, and another flanged plug detachably secured to said co-operating journal.
13. A mechanical musical instrument having roll-carrying journals, one of said journals being the usual driving-journal and the other the usual spring-pressed co-operating journal, in combination with a driving-plug 125

detachably secured to said driving-journal, and a coöperating plug swiveled to said co-operating journal.

14. A mechanical musical instrument having roll-carrying journals, roll-engaging plugs detachably mounted on the respective journals, and set-screws for fastening the respective plugs to said journals.

15. A mechanical musical instrument having roll-carrying journals, in combination with a hollow music-roll, plugs for engaging

the openings in said roll, and means for detachably securing said plugs to the respective journals.

In testimony whereof I have signed this specification in the presence of two subscribing witnesses.

EDWIN S. VOTEY.
